UNITED STATES PATENT OFFICE

ALEXENDER W. MARCOFSKY, OF CLEVELAND, OHIO.

HOT-AIR FURNACE.

SPECIFICATION forming part of Letters Patent No. 658,855, dated October 2, 1900.

Application filed January 10, 1900. Serial No. 983. (No model.)

To all whom it may concern:

Be it known that I, ALEXANDER W. MARCOFSKY, a resident of Cleveland, county of Cuyahoga, and State of Ohio, have invented 5 certain new and useful Improvements in Hot-Air Furnaces; and I do hereby declare the following to be a full, clear, and exact description of the invention, such as will enable others skilled in the art to which it pertains 10 to make and use the same.

My invention relates to improvements in hot-air furnaces.

The primary object of the invention is to provide a hot-air furnace with an improved 15 construction and arrangement of hot-air flues and to provide such an arrangement of hot-air flues relative to the combustion-chamber of the furnace as will result in a more thorough and economical utilization of the heat 20 generated by the products of combustion within the furnace.

Another object of this invention is to provide an improved construction of removably supporting a smoke-flue-engaging elbow centrally of the upper end of the combustion-chamber and render the said elbow not only 25 capable of being removed when it has been burned out and has to be replaced by a new elbow, but to render the elbow capable of being swung in a horizontal plane, so as to accommodate 30 itself into alinement with any smoke-flue extending from the furnace in a straight line to the chimney without requiring the employment of other elbows or bends in the line 35 of the smoke-flue and to accommodate the arrangement of the furnace with respect to the desired arrangement of the flue-supply aperture without interfering with a straight connection between the aforesaid elbow and 40 the chimney.

With these objects in view and to the end 45 of rendering the construction simple and durable and to the end of realizing other advantages hereinafter appearing the invention consists in certain features of construction and combinations of parts hereinafter described, and pointed out in the claims.

In the accompanying drawings, Figure I is 50 a side elevation, largely in central vertical section, of a hot-air furnace embodying my invention. Fig. II is a horizontal section on line II II, Fig. I, looking downwardly. Fig.

III is a horizontal section on line III III, Fig. I, looking upwardly. Fig. IV is a top plan of the fire-pot of the furnace. Fig. V is a 55 vertical section on line V V, Fig. IV. Fig. VI is a vertical section on line VI VI, Fig. IV. Fig. VII is a vertical section showing the connection of the smoke-flue-connecting elbow with the top of the smoke-chamber. 60

Referring to the drawings, *a* designates the lower portion or section of a fire-pot that is supported upon the shell or casing *c* of the ash-pit in the usual manner, and *g* represents the grate between the ash-pit and the fire-pot. 65 In the furnace illustrated the lower fire-pot section is a vertically-arranged open-ended cylinder composed of cast-iron.

b designates the upper fire-pot section, that is supported upon the upper end of the lower 70 fire-pot section *a* in any approved manner. The upper fire-pot section *b* consists, preferably, of an upwardly-flaring ring-shaped or annular casting. The upper fire-pot section *b* is provided with two series of upwardly-flanged apertures. *b'* represents the apertures of one of the said series of apertures. *b³* designates the flanges of the apertures *b'*, and *b⁴* represents the flanges of the other apertures *b²*. The apertures *b'* are arranged 75 at equal intervals or approximately equal intervals circumferentially of the fire-pot section *b* and in the main between the central portion and outer edge of the said fire-pot section. The furnace illustrated has six apertures *b'*. The fire-pot section *b*, as illustrated, has five apertures *b²*, arranged, respectively, centrally between two adjacent apertures *b'* and in the main between the central portion and the inner edge of the fire-pot section. The upper fire-pot section is provided, therefore, with two series of upwardly-flanged apertures, with the apertures of the one series and the apertures of the other series arranged alternately. The flanges 90 of all of the said apertures project upwardly and have their upper edges preferably in the same horizontal plane. The flanges of the apertures *b²* slightly overhang the chamber of the fire-pot. 95

The upper fire-pot section is composed of a single casting, and at its upper edge is provided with an external annular flange *b⁵*, that supports the casing of the smoke-chamber *d*. 100

d' designates the surrounding wall of the smoke-chamber, and d^2 the top of the said chamber. The top d^2 rests upon the upper end of the wall d' .

5 An air-chamber e (see Fig. I) surrounds the fire-pot, the ash-pit, and the casing of the smoke-chamber and extends a suitable distance above the smoke-chamber in the usual manner. The chamber e at the bottom is 10 provided with any suitable number of air-inlets e' and at its upper end has any suitable number of air-outlets e^2 .

The top d^2 of the smoke-chamber is provided with apertures d^3 , that are in open relation with the vertically-arranged air-flues f , that extend from the said top to and rest upon the flanges b^3 of the apertures b' of the upper fire-pot section. All of the apertures b' and b^2 of the upper fire-pot section are in open 20 relation with the air-chamber e . Hence the air-flues f are in open relation at their lower ends with the said air-chamber e at the outer side of the fire-pot and have their upper ends in open relation with the said air-chamber e at the top of the smoke-chamber. Air-flues h rest upon the upper edges of the flanges b^4 of the apertures b^2 of the upper fire-pot section and extend from the said apertures upwardly and over the fire-pot and have a 25 discharge-opening h' in common at their upper ends. In other words, the air-flues h converge upwardly and have their upper ends formed into an outlet in common centrally over the fire-pot. The said flues h and their 30 common outlet are formed, preferably, in one and the same casting.

The top d^2 of the smoke-chamber has apertures d^4 , that are engaged by the upper ends of air-flues k , that extend downwardly and 40 inwardly from the said top and terminate at their lower ends in an inlet k' , in common that registers with the common outlet h' of the flues h . In other words, several air-flues that are in open relation with the air-chamber e at the top of the smoke-chamber converge downwardly and are formed, preferably, in one and the same casting. By the provision of the flue-forming castings within the smoke-chamber the products of combustion 45 rising into or circulating within the said chamber are advantageously utilized. The casting composing the flues k rests upon the upper edges of the casting composing the flues h , and the lower wall of the last-mentioned casting at the bottom of the common 50 outlet for the flues forming the said casting is provided with an upward bulge, so as to form a small dome h^2 centrally above the fire-pot, which dome is open at the bottom. 55 The said dome is instrumental in the formation of an eddy of air within and below the same, so as to prevent overheating of the said dome-forming casting, and the said dome accommodates also an expansion of the dome-forming wall of the casting without injury to 60 the casting.

The top d^2 of the smoke-chamber is cen-

trally provided with an upwardly-flanged aperture d^5 , and d^6 designates the upwardly-projecting annular flange surrounding the 70 said aperture. A short flue m is secured to the said flange and depends from the latter into and centrally of and communicates with the upper portion of the smoke-chamber. The flue m has its upper end in open relation with the elbow n , that has its upright and inner portion embracing the aforesaid flange d^6 and provided with an external annular flange n' , (see Fig. VII,) that is seated upon the top d^2 of the smoke-chamber. The elbow 75 can be turned upon the top d^2 in a horizontal plane around the flange d^6 in the one direction or the other. In Fig. I the elbow is shown connected with a smoke-flue o , that leads to the chimney. (Not shown.) Several latches 80 r (see Fig. VII) for securing the elbow to the top d^2 are provided and arranged at suitable intervals along the edge of the flange n' . Each latch r is vertically pivoted or swiveled at one end, as at r' , to the top d^2 and has its 85 other end overlapping the upper side of the flange n' in the operative position of the latch. Obviously, the removal of the elbow n merely requires the swinging of the latches in the direction and to the extent required to release the elbow. 90

I have not illustrated any manner of packing the joints between adjacent or contiguous parts, because such packing can be done in any approved manner and forms no part 100 of my present invention.

What I claim is—

1. A hot-air furnace having a fire-pot; a smoke-chamber formed above and in open relation with the fire-pot; an air-chamber surrounding the smoke-chamber and the fire-pot, several air-flues in open relation with the air-chamber at the outer side of the fire-pot and arranged at suitable intervals about the fire-pot, which flues converge upwardly, are 105 formed in one and the same casting, and have their upper ends terminating in a common outlet, and several air-flues in open relation with the aforesaid air-chamber at the top of the smoke-chamber and converging downwardly from the said top, formed in one and the same casting and having their lower ends terminating in a common inlet that registers with the aforesaid outlet of the lower and upwardly-converging flues. 110

2. A hot-air furnace having a fire-pot; a smoke-chamber formed above and in open relation with the fire-pot; an air-chamber surrounding the smoke-chamber and the fire-pot, several air-flues in open relation with the air-chamber at the outer side of the fire-pot and arranged at suitable intervals about the fire-pot, which flues converge upwardly, are 115 formed in one and the same casting, and have their upper ends terminating in a common outlet, several air-flues in open relation with the aforesaid air-chamber at the top of the smoke-chamber and converging downwardly from the said top, formed in one and the same 120

125

130

casting and having their lower ends terminating in a common inlet that registers with the aforesaid outlet of the lower and upwardly-converging flues, and the lower wall 5 of the first-mentioned casting, at the bottom of the common outlet for the flues forming the said casting, being provided with an upward bulge so as to form a small dome h^2 centrally above the fire-pot, which dome is 10 open at the bottom, substantially as shown, for the purpose specified.

3. A fire-pot for a hot-air furnace divided centrally into two sections arranged one above the other, with the upper section flaring upwardly from the upper end of the lower section and having a series of upwardly-flanged air-conducting apertures formed in the inner and lower portion of the upper fire-pot section, and another series of upwardly-flanged 15 air-conducting apertures formed in the upper and outer portion of the said fire-pot section, substantially as and for the purpose set forth.

4. A hot-air furnace having a fire-pot that 20 is composed of two sections arranged one above the other with the upper section flar-

ing upwardly from the upper end of the lower section and having several upright flanged air-conducting apertures in its inner and lower portion, an air-chamber surrounding 30 the smoke-chamber and the fire-pot, a flue-forming casting upon the aforesaid flanges and leading from the aforesaid apertures upwardly and inwardly over the fire-pot and having the flues formed therein terminating 35 at the upper end of the casting in a common outlet, and another flue-forming casting resting upon the upper and outlet-forming end of the first-mentioned casting and having separate flues formed therein and leading upwardly and outwardly from the upper end of 40 the first-mentioned casting to the top of the smoke-chamber and there communicating with the aforesaid air-chamber, substantially as shown, for the purpose specified. 45

Signed by me at Cleveland, Ohio, this 31st day of October, 1899.

ALEXENDER W. MARCOFSKY.
